(57) **CLAIM**

We claim the ornamental design for a sensor bar for beehive monitoring, as shown and described.

DESCRIPTION

FIG. 1 is a top perspective view of a sensor bar for beehive monitoring, showing our new design;

FIG. 2 is a bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof;

FIG. 8 is a rear elevation view thereof; and,

FIG. 9 is a top perspective view, shown within an environment of use.

The broken lines depict environmental subject matter and forms no part of the claimed design.
